UNITED STATES PATENT OFFICE

126,070

DESIGN FOR A LOUD-SPEAKER CONSOLE

Arthur C. Haggstrom, Rockford, Ill., assignor to
E. H. Scott, Highland Park, Ill.

Application January 2, 1941, Serial No. 97,778

Term of patent 7 years

To all whom it may concern:

Be it known that I, Arthur Chas. Haggstrom, a citizen of the United States, residing in Rockford, in the county of Winnebago and the State of Illinois, have invented a new, original, and ornamental Design for a Loud-Speaker Console, of which the following is a specification, reference being had to the accompanying drawing, forming a part thereof.

The single drawing figure is a perspective view of a loud speaker console showing my new design.

The rear is plain and the opposite side is like that shown.

I claim:

The ornamental design for a loud-speaker console, as shown and described.

ARTHUR CHAS. HAGGSTROM.
